Application March 7, 1944, Serial No. 525,462

6 Claims. (Cl. 192—125)

1

This invention relates to magnetic detection and particularly to the detection of metallic material to permit the separation of magnetic from non-magnetic material and metallic from semi-metallic or non-metallic material.

The invention is especially applicable to the detection of "tramp metal" on conveyors which feed material such as ore or coal to crushers or other machinery, and to this end the invention includes means for detecting the presence of metallic or magnetic material, for producing resulting changes in an electric current, and by change in current, for controlling the desired apparatus which may include, for example, the motor driving the conveyor, a suitable signaling or other device, or both.

Occasionally in the material (hereinafter referred to as "ore") which is conveyed to the crusher, pieces of metal, usually iron or steel, are found. Such pieces of metal are likely to be parts of broken tools or machinery which have dropped into the ore during the mining or subsequent conveying thereof. If such pieces of metal, usually called "tramp metal" or "tramp iron" are not removed before they reach the crusher serious damage to the crusher or crusher machinery may result. Consequently, in accordance with the present invention, as the tramp metal approaches the crusher, it is caused to pass through a magnetic field set up by an energizing or exciter coil. The presence of tramp metal in the magnetic field whether the tramp metal be of magnetic or non-magnetic material, will distort the field. This distortion of the field will induce a potential or a change in potential in a pickup or detector coil suitably positioned in the field. The pick up or detector coil is connected to the input of a suitable amplifier, the output of which is connected to control circuits which will control the desired apparatus, such for example as the motor which drives the conveyor belt or a signaling device, or both.

A better understanding of the invention can be had from consideration of the following specification, taken together with the drawings, wherein:

Fig. 1 is a perspective view showing the relation of the exciter and pickup coils to a conveyor belt in accordance with the invention;

Fig. 1a is a modification of Fig. 1 showing the exciter coil positioned with its diagonal axis perpendicular to the longitudinal axis of the belt;

Fig. 2 is an elevational view of a conveyor belt and suitable supporting structures for the coils;

2

Fig. 3 is a sectional view in elevation taken along lines 3—3 of Fig. 4;

Fig. 4 is a sectional view taken along line 4—4 of Fig. 3; and

Fig. 5 is a diagram of the detection and control circuits.

Fig. 1 shows the general arrangements of the coils with respect to conveyor belt 27 which may be assumed to move from right to left, as seen in the drawing, and to be carrying ore to a crusher, for example. This belt should be of non-magnetic and preferably of non-metallic material. A piece of tramp metal 31 is represented as approaching coils 24 and 25 as it travels on belt 27. Coil 24 is the exciter coil and is shown in the drawing as being rectangular and positioned with its longer axis at right angles to the longitudinal axis of the belt, although it may be square. However, in certain cases it may be desirable that the exciter coil be positioned so that its diagonal axis is perpendicular to the longitudinal axis of the belt as shown in Fig. 1a. In the embodiment herein described, the exciter coil 24 may comprise approximately 481 turns of No. 14 insulated wire and will consume about 2.2 kv.-a., at very low power factor, when connected through leads 26 to an alternating current power source of 480 volts and 60 cycles.

The pickup or detector coil 25 may also be rectangular and is preferably positioned as shown in Fig. 1 with its longer axis perpendicular to the longitudinal axis of the belt and symmetrical with respect to the belt. In the embodiment referred to this pickup coil may comprise approximately 1735 turns of No. 18 insulated wire and its inside dimensions be approximately 34 inches by 8 inches. This coil is suitable for use with 60-cycle exciting current, and for a 36-inch wide conveyor belt. A different energizing frequency or belt width would, of course, require appropriate alterations in the design. Detector coil 25 is connected by leads 41 to the input terminals 1, 2 of a suitable amplifier preferably enclosed in the metal case 28. The component elements and connections of this amplifier will be described in connection with Fig. 5.

Coils 24 and 25 should be suitably protected from mechanical injury and should also be correctly supported with relation to each other and to the belt. In the contemplated embodiment these coils may normally be spaced approximately 24 inches from each other at their nearest points. It is preferable that the support for the detector coil be adjustable to permit the

spacing between the belt and detector coil to be changed when required, so as to accommodate different depths of material on the belt. In accordance with the invention, the supporting structure for the exciting coil includes a suitable casing to protect it from damage, and the supporting structure for the detector coil includes certain adjustable features which will be described in connection with Figs. 3 and 4. It will be noted in connection with Fig. 1 that the belt 27 passes between coils 24 and 25 and not through the center of either coil. This arrangement permits repair and changing of the belt without interfering with the coils or detection apparatus, and also permits the mentioned adjustment of the coil which is on the upper side of the belt. The positions of the exciter and detector coils may be reversed, although it is preferable that the detector coil be positioned on the upper side of the conveyor belt, viz., the side on which the ore is carried.

Fig. 2 illustrates the relation of the coil-supporting structures to the conveyor system. The figure shows a conventional conveyor system as used to feed an ore crusher, and in general comprises a conveyor belt 27 supported on suitable rollers 29. The belt is inclined in order to raise the ore so that it may drop by gravity into the crusher, and the rollers are arranged to dish the belt as shown in Fig. 4. The upper end of the belt passes around a traction wheel 30 which is driven by an electric motor 16. At a suitable position along the belt before it reaches the traction wheel, the magnetic exciter and detector coils are supported.

The coil-supporting structures are more clearly shown in Figs. 3 and 4. Exciter coil 24 is shown enclosed in a non-magnetic box 32, the sides and top of which may be of heavy plywood and the bottom of wooden planks, say 2 inches thick. If the top of the box is hinged the coil will be readily accessible but protected from injury and from dirt. The supporting platform 42 should be so located that the top of the box will be as close as possible to the bottom of belt 27 without being hit by it. Thus exciter coil 24 will be positioned close enough to the belt to assure that the magnetic field produced by the coil will permeate the ore conveyed on the belt.

The supporting structure for pickup coil 25 may, as shown in Fig. 3, comprise two A-frames 33 made of lumber of suitable dimensions. The legs of each of these frames are fastened together at the bottom by tie pieces 43, and both frames are fastened together at the tops by stringers 35 which straddle the conveyor belt. At the center of each A-frame is secured a vertical rail 36 which extends above the frame a few inches. Stringer pieces 35 are bolted to the extensions of these rails as shown, so that the stringers are spaced from each other a distance corresponding to the thickness of the rails 36, as shown in Fig. 3. A coil frame 34, which may also be made of wood, supports coil 25. This coil frame includes two extensions 44 on each end which slide along both sides of rails 36, permitting the entire frame 34 with its detector coil 25 to be moved vertically with respect to belt 27. To adjustably support the coil frame, two U-shaped metal straps 37 are secured around the sides and top of the frame near the ends thereof. To the centers of these straps are secured threaded rods or bolts 38 which pass through the space between stringer pieces 35. Across the tops of the stringer pieces are metal bearing plates 40. Nuts 39 engaging the

threaded rods 38 bear on these plates 40. Thus by turning the nuts 39 the frame 34 with its detector coil 25 may be adjusted vertically, viz., perpendicularly to the surface of the conveyor belt 27. Connecting leads 41 (Fig. 4) connect coil 25 to the input terminals 1 and 2 of the amplifier shown in Fig. 5.

An amplifier and control apparatus according to the invention are shown in the circuit diagram of Fig. 5. Vacuum tubes 3, 4 and 5 together with their associated circuit elements comprise a high gain amplifier which, in connection with coils 25 and 24, has been found to provide a sensitive, stable and readily adjustable magnetic detector system. The specific types of tubes which may be here employed and suitable constants for the associated circuit elements are given below.

The input of this amplifier, as has already been mentioned, is connected to terminals 1 and 2, and the output thereof is coupled across resistors R₁₅, R₁₁ and R₂₂ to a gas-filled grid-controlled "trigger" tube 6. This tube has the characteristic that with a positive potential on the anode 47 and a suitable negative control potential on the grid 48, the gas in the tube is not ionized and no anode current flows. However, when the negative control potential on the grid is decreased beyond a certain critical point the gas in the tube ionizes and anode current flows in the anode circuit wherein a suitable control device is connected. As soon as the gas is ionized the grid loses its control so that in order to open the anode circuit, viz., to stop anode current from flowing, the anode potential must momentarily be reduced substantially to zero.

The control device connected in the anode circuit of tube 6 comprises a relay L₁ having a winding which when energized by current in the anode circuit opens contacts 11. The control system 40 also includes a second relay L₂ having a single-contact armature 12 and a double-contact armature 13. This relay is so constructed that when current passes through its coil the contact 12 opens and armature 13 breaks its connection with contact 15 and closes its connection with contact 14.

A reset-device 7 together with its associated contact elements 8, 9 and 10, is provided and suitably connected to the relays so that operation of the reset device restores the entire system to its original condition after the system has been actuated as a result of the presence of tramp metal on the conveyor belt. Motor 16 of Fig. 5 is the same motor represented in Fig. 2, and, if desired, may be automatically disconnected to stop the conveyor belt when a piece of tramp metal is detected on the belt. Additional motors may be similarly controlled. The horn, or howler 19 comprises an audible signal or indicating device which may be actuated when tramp metal is detected and which continues to sound until the reset device is operated. Any other desired type of indicating or control apparatus may be added to or substituted for this audible indicator 19.

The full-wave rectifier tube 21 is connected to suitable windings on a power transformer 22 and to a filter comprising choke L₄ and condensers C₃ to provide a suitable source of direct-current potential to the other tubes in the system. Resistors R₁₂, R₆ and R₁₂₁ are connected as a voltage divider to provide the required potentials to the tubes. The entire system is energized from terminals 20 which may be connected to a suitable alternating current power source such as 75 120 volts, 60 cycles. The power for motor 16 is

derived from terminals 45 which may be energized for example from a 480 volt, 60 cycle line.

In the amplifier and control system above described the circuit elements may have the constants or be of the types indicated below:

C₁, C₁₁=.003 mfd. R₄=250,000 ohms.
 C₂=10 mfd. R₅, R₅₁=50,000 ohms.
 C₃=.1 mfd. R₆, R₆₁, R₆₂=10,000 ohms.
 C₄, C₄₁=20 mfd. R₇=500,000 ohms. (adjustable)
 C₅, C₅₁=4 mfd. R₈, R₈₁=100,000 ohms.
 C₆, C₆₁=.03 mfd. R₉=25,000 ohms.
 C₇, C₇₁=15 mfd. R₁₀=500,000 ohms.
 C₈=8 mfd. R₁₁=10,000 ohms. (adjustable)
 C₉=.5 mfd. R₁₂, R₁₂₁=3,000 ohms.
 C₁₀=.01 mfd. L₄=15 H.
 R₁=60,000 ohms 3=6J7 tube.
 R₂, R₂₁, R₂₂=1,000 ohms 4=6C5 tube.
 R₃=1.0 megohm 5=6N7 tube.
 6=2A4G tube.

It is to be understood that the particular circuit arrangement and circuit elements and constants herein set forth, are given only by way of example in connection with the present description of a preferred embodiment of the invention, and that the scope of the invention is not to be limited thereby.

Operation

The operation of the magnetic detector system above described is as follows: A direct-current potential of about 200 volts, derived at the tap between resistors R₁₂ and R₆, is applied to the anode 47 of tube 6, and a negative bias such as to block the tube is derived from potentiometer R₁₁ and is impressed on the grid 48 of tube 6. Thus, in the absence of a sufficient alternating-current potential super-imposed on the grid of tube 6, the control system does not operate. However, when a potential or change of potential of correct sign and magnitude, due to a disturbance in the magnetic field impressed on detector coil 25, is impressed across input terminals 1, 2 of the amplifier, the negative bias on the grid 48 of tube 6 will be instantaneously decreased below its critical value, permitting the gas in the tube to ionize, thus establishing anode current in the anode circuit thereof and actuating relay L₁ connected in the anode circuit. When relay L₁ is actuated its armature is locked in actuated position by means of latch 46, holding contacts 11 closed. Contacts 11 are connected in series with the actuating coil of relay L₂ across the power line 20. Hence, closure of contacts 11 operates relay L₂, opening contacts 12 and 13-15, and closing the connection between armature 13 and contact 14. The opening of contacts 12 opens the anode circuit of gas tube 6, thus deionizing that tube and permitting grid 48 to resume control upon subsequent closing of contacts 12. Assuming switch 17 to be closed and switch 18 open, such operation of relay L₂ also opens the circuit to traction motor 16 and closes the circuit to howler 19, thus immediately stopping the conveyor belt 27 and simultaneously producing an audible signal calling the attention of an attendant to the fact that tramp metal has been detected on the conveyor belt. These conditions will persist until the reset device 7 is operated. The operation just described is practically instantaneous, so that the attendant will find the detected tramp metal under or just beyond the detector coil at its position over the conveyor belt.

When the system operates with switches 17 and 18 closed, the motor 16 will not be stopped,

but howler 19 will give an audible signal as the tramp metal passes within the field of the detector coil 25 and will continue to sound until the reset device 7 is operated. In this manner the attendant can remove the piece of tramp metal without interrupting the operation of the conveyor. Should no audible signal be desired switches 17 and 18 may be kept open, in which event the conveyor traction motor 16 will automatically be stopped when tramp metal is detected, and will remain so until the reset device 7 is operated, although the howler will not sound.

Reset device 7, electrically is in the nature of a push button, but in an installation of the type herein considered it may preferably take the form of a large and rugged switching means or device preferably secured above the head of the attendant and arranged to be operated manually by pulling on a cord suspended from the device. Operation of reset device 7 first closes contacts 8 and 9, and as the cord is pulled further down also closes contacts 9 and 10. Suitable springs restore the contacts to open-circuit position upon release of the cord. Closure of contacts 8 and 9 actuates relay L₂ when contacts 11 of relay L₁ are open. Thus, as long as contacts 8 and 9 are held closed the motor 16 will remain stopped, and howler 19 will sound providing switch 17 is closed. This is a convenient manner in which to test the control and signaling apparatus as well as to permit the attendant to stop the conveyor belt in an emergency. As reset device 7 is further actuated to close contacts 9 and 10, release coil L₃ is energized, releasing latch 46 and allowing contacts 11 to be opened by a spring. Thus, immediately upon the release of reset device 7, opening contacts 8, 9 and 10, relay L₂ is no longer energized, whereby contacts 12 will close the anode circuit of tube 6 and restore the control system to its normal condition. Also, armature 13 will make connection with contact 15 thereby connecting driving motor 16 to the line 45 and restoring the conveyor belt to operation.

The adjustable resistor R₁₁, which is preferably of the potentiometer type, should be set at a point which will permit stable operation when the reset device is operated, i. e., when the reset device 7 is released and contacts 12 close, the anode voltage is suddenly applied to tube 6 and may have a tendency to "trigger" this tube unless sufficient margin of grid bias is impressed on grid 48. The value of this grid bias is adjusted by resistor R₁₁ and with the proper setting thereof the reset device 7 may be operated and released with no danger of triggering the tube 6.

The system may be initially adjusted as follows: Adjustable resistor R₇, which may also be of the potentiometer type, may first be set about midway of its adjustment range; then resistor R₁₁ is adjusted to increase the bias on grid 48 until repeated operation of the reset device does not trigger tube 6. Resistor R₇ is then varied to adjust the gain of the amplifier to a point where the entire detector system will operate specifically to detect metal of the type and minimum proportions which it is desired to detect. If, with resistor R₇ at such adjustment, it be found that with no metal near coil 25 the residual "balance" voltage in coil 25 tends to trigger tube 6, such tendency can be overcome by increasing the bias on grid 48 by further adjustment of resistor R₁₁, or by adjusting the spatial and hence the balance relation between coils 25, 24. After these adjustments have been effected, the system accord-

ing to the present invention will detect with complete reliability all pieces of metal down to the minimum proportions of that for which the system was initially adjusted.

The present invention has been described in connection with a system for detecting tramp metal on a conveyor belt, but it is not limited thereto, as those skilled in the art will at once appreciate, for it has many different and additional applications.

What is claimed is:

1. In a system for detecting tramp metal among other material on a conveyor, an alternating-current exciter coil located on one side of said conveyor so that said material passes through the field of said coil, a detector coil located on the other side of said conveyor in the field of said exciter coil, an alternating current vacuum tube amplifier having an input and an output, said detector coil being coupled to said input so as to impress a voltage thereon, a control system, said output being coupled to said control system, a motor for driving said conveyor, control means connected in said control system operable in response to change of current in said output, switching means actuated by said control means, connections between said switching means and said motor, said switching means being operable to open the connections to said motor upon operation of said control means, locking means retaining said connections open, and manually operable means for releasing said locking means.

2. In a system for detecting tramp metal among other material on a conveyor, an alternating-current exciter coil located on one side of said conveyor so that said material passes through the field of said coil, a detector coil located on the other side of said conveyor in the field of said exciter coil, an alternating current vacuum tube amplifier having an input and an output, said detector coil being coupled to said input so as to impress a voltage thereon, a control system, said output being coupled to said control system, a driving motor for said conveyor, a detection-indicating device, switching means in said control system connected to said motor and to said device and operable in response to change of current in said output, connections between said switching means, said motor and said device whereby operation of said switching means may automatically control said motor and said device, and second switching means for selectively connecting said motor or said device, or both, to said control system for automatic control by said first mentioned switching means.

3. In a system according to claim 1, adjustable supporting means for supporting said detector coil in adjustable spatial relation to said exciter coil so as effectively to adjust the voltage from said detector coil which is impressed on the input of said amplifier.

4. In a system according to claim 2, support means for supporting said detector coil in fixed relation to said exciter coil, means for moving said detector coil on said support means to adjust the spacing between said detector coil and said exciter coil and adjustable resistor means connected in the input of said amplifier so as effectively to adjust the voltage from said detector coil which is impressed on the input of said amplifier.

5. In an inspecting system for detecting magnetic materials, said system being of the type including an electric motor for moving material to

be inspected, an alternating-current exciter coil and a detector coil positioned in the magnetic field of said exciter coil, the combination which comprises, a power source, a vacuum tube amplifier having an input and an output, means for coupling said input to a detector coil, a gas-filled grid-controlled tube having a grid circuit, an anode and an anode circuit, said grid circuit being coupled to said amplifier output, a source of anode potential connectible to said anode, a first relay having an actuating coil connected to be energized by current in said anode circuit and having contacts which are closed by actuation of said relay, a second relay having an actuating coil connected in series with said power source and the contacts of said first relay such that actuation of said first relay actuates said second relay, a first set of contacts on said second relay arranged to open on actuation and to close on de-actuation of said second relay, said first set of contacts being connected in series in said anode circuit between said source of anode potential and said anode, a second set of contacts on said second relay, a motor, an electric power source for said motor, and circuit connections between said motor power source, said motor and the second set of contacts on said second relay whereby closure of said second set of contacts connects said motor to said motor power source.

30 6. In a magnetic detector system of the type including an alternating current exciter coil and a detector coil positioned in the magnetic field of said exciter coil, the combination which comprises, a power source, a vacuum tube amplifier having an input and an output, means for coupling said input to said detector coil, a gas-filled grid-controlled tube having a grid circuit, an anode and an anode circuit, said grid circuit being coupled to said amplifier output, a source of anode potential connectible to said anode, a first relay having an actuating coil connected to be energized by current in said anode circuit and having contacts which are closed by actuation of said relay, a second relay having an actuating coil connected in series with said power source and the contacts of said first relay such that actuation of said first relay actuates said second relay, a first set of contacts on said second relay arranged to open on actuation and to close on de-actuation of said second relay, said first set of contacts being connected in series in said anode circuit between said source of anode potential and said anode, a device to be controlled, a second set of contacts on said second relay connected to control the operation of said device, a latch associated with said first relay and arranged upon actuation of said first relay automatically to maintain said first relay in actuated position after the actuating coil thereof is de-energized, switching means having first and second switch contacts arranged so that upon actuation thereof the first switch contacts close before closure of the second switch contacts, a latch coil associated with said first relay and operative when energized to release said latch, circuit connections between said first switch contacts, said power source and the actuating coil of said second relay such that closure of said first switch contacts actuates said second relay, and circuit connections between said power source, said second switch contacts and said latch coil, such that closure of said second switch contacts energizes said latch coil and releases said latch

35 40 45 50 55 60 65 70 75

after said second relay is actuated, thus to restore said first relay to deactuating condition.
